UNITED STATES PATENT OFFICE

BERTRAL SARRETT, OF NASHVILLE, TENNESSEE

SANITARY DEVICE FOR WATER-CLOSET BOWLS

Application filed July 18, 1928. Serial No. 293,650.

This invention relates to improvements in sanitary devices for water closet bowls, one object of the invention being the provision of an electrical air exhaust device readily attachable to bowls of this type and provided with means which when the seat is occupied will withdraw the foul air from within the bowl and exhaust the same to the outside air.

19 A further object of this invention is the provision of a motor actuated exhaust fan which is attached to the bowl through the seat hinging elements and in which the air admitting member is positioned within the 15 bowl adjacent the seat with the exhaust leading to the atmosphere, there being a switch normally open, which when the seat is occupied is closed to cause the energization of the 20 fan driven electric motor and consequently the exhaust of the foul air during the period of use.

A still further object of this invention is the provision of a device of this character which is simple, inexpensive and durable in 25 construction and thoroughly efficient and practical in use, and which is easily installed.

In the accompanying drawings:—

Figure 1 is a perspective view of a water 30 closet bowl with the present invention applied.

Figure 2 is a side elevation of the device per se.

Figure 3 is a top plan view thereof.

Figure 4 is a section on line 4—4 of Figure 3.

Figure 5 is a vertical cross section through the fan casing, showing the upper end of the motor.

Figure 6 is a plan view of the bottom plate 40 of the fan casing with the fan in elevation.

Referring to the drawings, B designates the water closet bowl, S the seat and C the cover of lid therefor.

The air inlet member or nozzle 9 is provided with the oppositely extended apertured supporting or attaching lugs 8, which fit upon the lid carrying lugs 7 of usual construction, the nozzle being adapted to have its free end as shown in Figure 3 projected within 50 the upper edge of the bowl, so that when the

seat is occupied, the air will be drawn from within the bowl and the nozzle will be out of the way and not be subject to the flushing water. The air directing tubular member 11 is a part of the nozzle and though shown here substantially cylindrical can be made tapering from the far end toward the supporting portion thereof. The curved end 12 is flanged and attached to the air inlet end of the fan chamber or casing 13, while the 60 exhaust 14 through the coupling 15 is attached to a directing pipe 16 to the outside air.

As shown the inlet end 33 of the nozzle 9 is curved and covered by the screen 34, held 65 in place by the clamp 35.

An electric motor 17 depends from the fan casing and its shaft 18 journaled in the lid 19 of the casing 13, operates the rotary fan or blower 20, and said shaft is lubricated by 70 means of the oil directing tube 21.

In order that the motor may be energized when desired, that is when the seat is occupied, the support 22 is attached to and carried by the tubular member 11, and carries 75 the switch 23, which is a normally open one. The rubber switch engaging member 24 is adjustably carried by the screw 25, which is carried in the threaded lug 26, which lug in turn is mounted upon the free end of the 80 switch closing lever 27. This lever 27 is pivoted to the lug 10, and in its free end is carried the roller pin 32 which engages the under side of the seat, the spring 28, connected to the switch operating end of the 85 lever and adjusted through the screw 29 carried by the arm 30 being sufficiently tensioned as to prevent the switch being closed until the seat is occupied, at which time the button 24 is pressed against the switch 23 90 and the circuit to the motor closed. The plug 33' and cord 34' form the means to connect the switch and motor in series.

From the foregoing description taken in connection with the drawings, it is evident 95 that a sanitary device, which is readily attachable to a water closet bowl is provided and one which will withdraw all of the foul air within the bowl and exhaust the same to the atmosphere, thus preventing such air from 100

entering the toilet room or bath room, and providing a much needed sanitary apparatus.

Although in the drawings the present construction is shown as applicable only on the right hand side of the bowl, by making the nozzle separate and attachable to the remainder of the apparatus, the device can be made universal, that is so that the motor can be placed upon either right hand or left hand side of the bowl.

It is also desirable in installing to place two strips of rubber upon the underside of the seat to leave an open space at the front of the bowl, thus causing the air drawn in to pass across the bowl and into the suction nozzle.

What is claimed is:—

1. The combination with a water closet bowl, a seat, a hinging element for said seat, a foul air exhausting device secured in position by said hinging elements and comprising a nozzle having apertured lugs to engage the hinging element, a fan casing having an exhaust to the atmosphere carried by the nozzle, an electric motor for operating the fan, a switch supported by the nozzle, said switch being normally open, and in circuit with the motor, a lever also pivoted to the nozzle, an adjustable switch operating member carried by the lever, a spring for holding the same away from the switch, and means carried by the free end of the lever and in the path to be engaged by the seat when occupied to close the switch through the depressing of the lever at the free end.

2. In a sanitary device of the character described, the combination with a bowl and its hinged seat, a flat nozzle adapted to fit between the inner edge of the said seat and bowl and having an air directing portion, a pair of horizontal lugs to receive the seat fastenings and also having a single vertical lug at one side, a lever pivoted intermediate its ends to said vertical lug, a spring connected to the outer end of said lever for holding its inner end normally in contact with said seat, a casing in communication with the air directing portion of said nozzle, a fan in the upper portion of said casing, a motor in the lower portion of said casing on the shaft of said fan, a switch connected to said air directing portion of said nozzle and with the outer end of said lever and normally held open, and electrical connections with said switch and motor.

In testimony whereof I hereunto affix my signature.

BERTRAM SARRETT.
